(57) **CLAIM**

The ornamental design for a portable information terminal, as shown and described.

DESCRIPTION

FIG. 1 is a rear, top, right perspective view of a portable information terminal showing my new design; FIG. 2 is a rear, bottom, left perspective view thereof; and, FIG. 3 is a rear elevational view thereof.

Portions in broken lines are for illustrative purposes only and form no part of the claimed design. Dot-dash broken lines define the boundaries of, but not included in, the claimed design.

1 Claim, 3 Drawing Sheets

FIG.1

FIG. 3
